US00D894884S

(12) United States Design Patent **(10) Patent No.:** **US D894,884 S**
Park et al. **(45) Date of Patent:** **** Sep. 1, 2020**

(54) ELECTRONIC DEVICE

(71) Applicant: **SAMSUNG ELECTRONICS CO., LTD.**, Suwon-si (KR)

(72) Inventors: **Hyounghsin Park**, Seoul (KR); **Seungho Jang**, Seongnam-si (KR); **Dongkyun Kim**, Seoul (KR); **Seonkeun Park**, Seoul (KR); **Yunjin Kim**, Seoul (KR)

(73) Assignee: **SAMSUNG ELECTRONICS CO., LTD.**, Gyeonggi-Do (KR)

(***) Term: **15 Years**

(21) Appl. No.: **29/656,273**

(22) Filed: **Jul. 11, 2018**

(30) Foreign Application Priority Data

Jan. 12, 2018 (KR) 30-2018-0002051

(51) LOC (12) Cl. **14-03**

(52) U.S. Cl.

USPC **D14/248**

(57) CLAIM

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an enlarged view of the encircled portion 9 in FIG. 6.

The even-dash broken lines illustrating portions of the electronic device form no part of the claimed design. The dot-dash broken lines in the figures represent a boundary line and form no part of the claimed design. The dot-dot-dash broken lines encircling enlargement portions of the claimed design form no part of the claimed design.

1 Claim, 7 Drawing Sheets
